[57] ABSTRACT

A footspa cabinet for bathing and exercising the legs and feet of the user under a spray of hot water. Rollers are mounted in the cabinet under the location of the feet, to permit the foot muscles to be exercised. The apparatus includes a pump which forces a spray of water against each enclosed leg and foot, and a heater which maintains the recirculated water at a temperature regulated by a thermostat. The enclosure of the cabinet is formed of two shells which buckle together to form a waterproof sealed housing and to enclose both legs and feet of a user.

FIG. I

FOOTSPA CABINET

BACKGROUND OF THE INVENTION

1. Field of Invention

This invention relates to a cabinet for bathing and exercising the legs and feet of a user under a spray of temperature controlled water.

2. Prior Art

Enclosed cabinets have been utilized for foot baths, but the advantage of this invention lies in the provisions for spraying hot water on both the feet and the legs, together with the location of rollers, under the feet position, for providing foot exercises under muscle-tension relieving conditions provided by the hot water spray.

SUMMARY OF THE INVENTION

The invention consists of a portable cabinet for enclosing the feet and lower legs with apparatus for heating and spraying recirculated water against the enclosed feet and legs, together with a series of freely mounted rollers located as footrests, which provide exercise to the feet, when manipulated by the user.

BRIEF DESCRIPTION OF THE DRAWINGS

The objects and features of the invention may be understood with reference to the following detailed description of an illustrative embodiment of the invention, taken together with the accompanying drawings in which:

FIG. 1 is a perspective view of the apparatus being utilized by a seated user; and

FIG. 2 is a sectional view in elevation of the apparatus.

DESCRIPTION OF THE PREFERRED EMBODIMENT

Turning now descriptively to the drawings, in which similar reference characters denote similar elements throughout the several views, FIG. 1 illustrates the apparatus 10, enclosing the lower legs 11 of the user who is seated on an adjoining chair 12.

As shown in FIG. 1-2, the apparatus 10 is formed of a lower cabinet section 40, which is matingly attached 45 to an upper shell 41 by hingeable bracket clips 13. Clips 13 fasten together the flanges 15 along the open edges of the upper shell 41 to flanges 15 located along the sides of the lower cabinet 40, with the upper cabinet walls 42 snugly riding inside the sides 17 of the 50 upper shell 41 to provide a watertight seal.

Flexible rubber or plastic sleeving 38 encircles the two openings 19 in the top face 18 of the upper shell 41 to provide watertight seals about the legs 11 of the user which are inserted through each of openings 19 to 55 the top cover 18.

A flexible power supply cord 14 furnishes a supply of electricity to the equipment, which may be alternately powered by internal batteries.

The inside of the lower cabinet 40 is fitted with free-rotating rollers 20 upon which the feet 17 may be placed so as to exercise the foot muscles under the tension-relieving conditions of the hot water spray which is injected at the legs by sprayer nozzles 25 mounted in the interior wall 35 of the lower cabinet 40, and at the feet 17, by sprayer nozzles 22 which are located below and in between the rollers 20.

A supply of water or other solution, including medication, is added to the interior of the lower cabinet 40 prior to use, and flows through vertical tubular opening 24 to a water chamber 44 located in the lowest section 5 of the interior of the lower cabinet 40, in which an enclosed electric-motorized pump 30 is located. Pump 30 draws the water from chamber 44 and forces it under pressure into tubular section 23 above the chamber 44 and through tubes 26 in the walls 16 and 42 of the lower chamber, where the water is released through sprayer nozzles 22 and 25 respectively, at the feet and legs of the user.

The water 37 returns to chamber 44 by rolling down inclined interior walls 35 surrounding the leg area, and 15 through openings 36 in the collection tube 24 surrounding the feet area.

An electrical heater 31 is located in the water chamber 44 for heating the water in the chamber to a temperature regulated by thermostat 32 which is controlled by rotatable shaft 34 and external attached knob 33.

The apparatus permits the user to obtain relaxation of his foot muscles under the tension relieving effects of the hot water spray, and to exercise his muscles in 25 the relaxed condition by rolling the soles of his feet and his toes against rollers 20.

Since obvious changes may be made in the specific embodiment of the invention described herein, such modifications being within the spirit and scope of the 30 invention claimed, it is indicated that all matter contained herein is intended as illustrative and not as limiting in scope.

Having thus described the invention, what I claim as new and desire to secure by letters Patent of the United States is:

1. Apparatus for exercising the feet under a spray of controlled-temperature hot water comprising a cabinet which houses free rotatable rollers against which the soles of the feet of the user may be rested, together with

a recirculating water system including an electrically motorized pump which draws water from a gravity-fed chamber and forces it through spray nozzles directed at the feet and the lower legs of the user, and means to direct said sprayed water so as to be collected and heated by an electrically operated heater prior to being redrawn by the pump from the gravity-fed chamber, together with

a thermostat switch for controlling the operation of the electrically operated heater, said thermostat switch being regulated by means external to the apparatus, together with

a housing which encloses the apparatus in a watertight manner, said housing being formed of two sections which are portable, together with means to tighten said sections together in watertight sealed condition, with one section of the housing formed with two openings, each of a size to admit a leg of the user, with the periphery of each of said openings wrapped with a flexible seal so as to seal each of the openings against the inserted legs of the user.

2. The combination as recited in claim 1 in which an external flange is mounted along the parting edge of each separable section of the housing, with said flanges nesting against each other in the fastened mode.
